UNITED STATES PATENT OFFICE.

CLARENCE D. CONNER, OF TUPELO, MISSISSIPPI.

ATTACHMENT FOR PAPER CUTTERS OR KNIVES.

1,216,950.

Specification of Letters Patent. Patented Feb. 20, 1917.

Application filed May 24, 1916. Serial No. 99,582.

To all whom it may concern:

Be it known that I CLARENCE D. CONNER, a citizen of the United States, residing at Tupelo, in the county of Lee and State of Mississippi, have invented new and useful 5 Improvements in Attachments for Paper Cutters or Knives, of which the following is a specification.

This invention relates to an attachment 10 for paper cutters or knives by means of which manual clawing of paper is obviated.

The primary object of the invention is to provide a construction by means of which the end of the paper may be moved to a position 15 to be readily grasped by the operator and thus destroy the cohesive action between the edge portion of the paper and the body portion of the roll.

An object of the invention is the novel 20 manner of associating the hand wheel with the rest of the elements so that this single element will be capable of rotating through intermediate elements, the roll and moving another element into position to separate the 25 edge portion of the paper from the roll so that the same can be readily grasped by the operator.

A very important feature of this arrangement is that one hand of the operator can 30 perform the dual function of rotating the roll and separating the edge portion while the remaining hand will be free to move the sheet of paper thus liberated over the cutting knife.

With these and other objects in view the invention will be better understood from the 35 following detailed description taken in connection with the accompanying drawings wherein—

Figure 1 is a front elevation of a paper 40 rack, showing my invention applied thereto.

Fig. 2 is an end elevation thereto.

Fig. 3 is a section on the line 3—3 of Fig. 1.

Fig. 4 is a longitudinal sectional view 45 through the entire apparatus.

Figs. 5 and 6 are detailed views of certain elements.

Referring to the drawings, the numeral 1 50 designates a frame or paper cabinet of a well known construction comprising a base 2, uprights 3 and a top plate 4. Journaled in the uprights is a rectangular shaft 5 upon which is adjustably mounted serrated cone bearings 6 held in place by means of a set

screw 7. These cone bearings have a binding action with the usual bore 8 formed at the center of the roll of paper 9.

The paper cutting knife 10 is supported by means of the brackets 11 and yieldably 50 forced toward the roll by means of coil springs 12 encircling and acting upon an intermediate portion of each bracket.

In the drawings, I have shown my invention in duplicate form arranged at both ends 65 of the shaft, but I will limit the following description to only those elements arranged at one end of the shaft, as a description of one will suffice for a description of the other.

Rotatably mounted upon one end of the 70 knife 10 is a crank shaft 13, the end portions 14 and 15 of which being angularly disposed for a purpose hereinafter described. Also secured to the blade or knife is a release

spring 16 yieldably engaging the crank portion 17 of the shaft so as to yieldably hold the shaft in either of its two positions. The end portion 15 of the shaft has secured thereto a shoe 16' shown in this particular instance as made of yieldable material such 75 as rubber, but I wish it to be understood that the same can be made of any suitable material and of any suitable shape depending upon whether the shoe is to force its way between the edge of the paper and the roll or to create an adhesive action between the shoe and the edge portion of the paper greater than the cohesive action between the edge portion and the roll. The end portion 14 has secured

thereto one end of a flexible element 18 that 80 passes through a number of guide elements 19 and secured to one end of a centrally pivoted lever 20, one arm 21 of which abuts an expansion spring 22 supported by one side of the uprights. Slidably mounted on the 85 protruding end 23 of the shaft and held against rotary motion around the shaft due to the configuration of the latter is a hand wheel 24. This hand wheel 24 is so disposed that upon sliding it upon the shaft the arm 90 21 of the lever will be engaged for moving the arm in opposition to the spring with the result that the other end of the lever will be moved in a direction to exert a pull upon the element 18 which causes the crank shaft to 100 be rotated in a direction to throw the shoe 16' into engagement with the roll 9.

The coöperation between the hand wheel 105 and the shaft allows the hand wheel to turn the roll so that the roll may be rotated subse- 110

quently to the positioning of the shoe 16'. Upon the wheel 24 being relieved of pressure the spring 22 returns the parts to normal position.

5 From the foregoing description it will be seen that by having the elements arranged as shown one hand of the operator is capable of manipulating the hand wheel 24 so as to initially throw the shoe 16' into proper 10 relation with the roll and to subsequently give rotary movement to the roll so that the shoe may have the proper action upon the edge portion of the paper. A very important feature of my invention is the fact that 15 the shoe moves in a plane below the edge of the knife so that the cutting action between the knife and paper is not interfered with.

It is to be understood that while all of the several features of my improved apparatus 20 have special coöperation with one another and together constitute a particularly effective mechanism for the purpose in view, certain of these features may be applied in other relations such as dispensing with the 25 hand wheel 24 and lever 20 and so disposing the spring 22 as to exert tension upon the element 18 for continuously holding the shoe in engagement with the roll. I therefore desire to cover the combination comprised in the several parts of my improved 30 apparatus whether employed in the general organization shown or elsewhere.

What I claim is:

1. An attachment for a paper cutting 35 knife, a shoe, a crank shaft rotatably mounted upon the knife and supporting the shoe for movements toward and away from the paper, resilient means coöperating with the crank portion of the shaft for resiliently 40 holding said shoe in either of its two positions, and means for giving movements to said shaft.

2. An attachment for a knife of the class described comprising a crank shaft rotatably 45 mounted on the knife, a shoe connected to one end of said shaft for movements under the knife edge toward and away from the paper, means for giving movements to said shaft, and resilient means coöperating with 50 the crank portion of the shaft for holding said shoe in either of its two positions.

3. In combination a frame, a shaft journaled therein and supporting a roll of paper, a knife, a shaft mounted on the knife and 55 having one end disposed to press against the roll directly below the knife, and means for

normally holding said end out of engagement with the roll.

4. In combination a frame, a shaft journaled therein and supporting a roll of paper, 60 a knife, a shaft mounted on the knife and having one end disposed to press against the roll directly below the knife, and means having a portion arranged exteriorly of the frame whereby said end may be manually 65 moved out of engagement with the roll.

5. In combination a frame, a shaft journaled therein and supporting a roll of paper, 70 a knife, a shaft mounted on the knife and having one end disposed to press against the roll directly below the knife, a flexible element having one end connected to said shaft, a spring pressed lever connected to the other end of said element, and means for simultaneously giving movement to said 75 lever and the roll.

6. In combination a frame, a shaft journaled therein and supporting a roll of paper, 80 a knife, a shaft mounted on the knife and having one end disposed to press against the roll directly below the knife, a flexible element having one end connected to said shaft, a spring pressed lever connected to the other end of said element, and means for simultaneously giving movement to said 85 lever and the roll, said means including a shaft rotatably supporting the roll of paper, and a hand wheel for giving movements to the shaft and said lever.

7. In combination a frame, a shaft journaled therein and supporting a roll of paper, 90 a knife, a shaft mounted on the knife and having one end disposed to press against the roll directly below the knife, a flexible element having one end connected to said shaft, a spring pressed lever connected to the other end of said element, a resilient shoe attached to said end of the shaft, a flexible element having one extremity connected to the remaining end of said shaft, a 100 spring pressed pivoted lever connected to the other extremity of said element, a shaft rotatably supporting the roll of paper and a hand wheel slidably mounted on the shaft 105 and adapted to give movements to said shaft and movements to said lever.

In testimony whereof I affix my signature.

CLARENCE D. CONNER.
